DECORATIVE FENCE

Erwin T. Massa, Park Ridge, and Cynthia J. Imbrie,
Palatine, Ill., assignors to Contractors' Components
Inc., Wheeling, Ill., a corporation of Illinois

Filed Nov. 28, 1960, Ser. No. 62,998

Term of patent 14 years

(Cl. D28—1)

Fig. 1.

Fig. 2.

Fig. 3.

Fig. 4.

Fig. 5.

Fig. 6.

Fig. 7.

FIGURE 1 is a front perspective view of a decorative fence embodying our new design, a portion of the right end panel being broken away for convenience of illustration;

FIGURE 2 is a front elevational view thereof on a reduced scale, the rear being substantially the same;

FIGURE 3 is a top plan view thereof as shown in FIGURE 2;

FIGURE 4 is a right end elevational view thereof on an enlarged scale;

FIGURE 5 is an enlarged fragmentary front elevational view showing the right end thereof;

FIGURE 6 is an enlarged fragmentary top plan view showing the connection between the last two right end panels; and

FIGURE 7 is an enlarged fragmentary top plan view of the right end thereof.

We claim:

The ornamental design for a decorative fence, substantially as shown and described.
